WYMAN C. PARKER, OF DETROIT, MICHIGAN, ASSIGNOR TO CLARK W. PARKER, OF DETROIT, MICHIGAN.

TANK FOR RUST-PROOFING METALS.

1,185,343.

Specification of Letters Patent.

Patented May 30, 1916.

Application filed January 12, 1916. Serial No. 71,624.

To all whom it may concern:

Be it known that I, WYMAN C. PARKER, a citizen of the United States, and residing at Detroit, in the county of Wayne and State of Michigan, have invented a new and Improved Tank for Rust-Proofing Metals, of which the following is a specification.

This invention relates to double tanks especially adapted for the treatment of metals by means of acid baths under the influence of sufficient heat to set up currents of the liquids within the tanks, and its object is to provide a double tank wherein the liquid may be heated in an outer receptacle and then flow into an inner receptacle without agitating any deposits or precipitates in such inner receptacle.

This invention consists of a plurality of receptacles, one within the other and spaced therefrom, the bottom and lower portion of the inner receptacle being imperforate, and the height of the liquid in the outer receptacle and the construction of the inner receptacle being such that the heated liquid may circulate freely from one receptacle to the other.

It further consists in supplying the inner receptacle with a discharging device to permit the decanting of the contents of the inner receptacle down to a certain predetermined level.

In the accompanying drawings, Figure 1 is a plan of this improved double tank, a portion of the rims of the outer casing and outer receptacle being broken away. Fig. 2 is a central longitudinal section of the double tank. Fig. 3 is a cross section of this double tank on a larger scale. Fig. 4 is a cross section of a modified form of this double tank. Fig. 5 is a horizontal section and Fig. 6 is a vertical section of portions of the outer casing. Fig. 7 is a vertical section of the discharge valve.

Similar reference characters refer to like parts throughout the several views.

The structure shown in the drawings consists of inner and outer receptacles and an outer shell or casing adapted to prevent loss of heat as far as possible, and built up of side plates 1 and end plates 2, both lined with sheets 3 of asbestos. These plates may be secured together by means of bolts 4 as shown in Fig. 5. Burner pipes 5 may extend near the bottom of the casing and

connect to the air pipe 6 and gas pipe 7 by means of valves 8.

The outer receptacle may be supported in any desired manner, short pillars 10 being preferred. It is preferably formed with a flat bottom 12 and with vertical sides 13 and 14, and positioned near its bottom relative to the casing by small angle-iron brackets 15 if desired. An angle bar 16 is preferably secured to the upper edge of this outer receptacle and to the upper edge of the casing by means of the bolts 17. The products of combustion may escape from the space between the casing and the outer receptacle through the flue 18 and through the holes 19 (Fig. 3), although either may be omitted if desired. A cover 20 for this tank may be hinged to the angle bar 16 if desired.

The inner receptacle is removable and is shown resting on the I beams 22 which are preferably cut out just above the burner tubes 5 to permit free flow of the liquid within the outer receptacle. The inner receptacle consists of an imperforate bottom 23, and the sides 24 and ends 25 formed with holes 26 through which the liquid in the tank may flow freely.

Secured to the bottom 23 around an opening 27 is a threaded ring 28 (Fig. 7) into which the short pipe 29 is screwed. The upper end of this pipe is formed into a seat 35 for the valve 30 which is made quite heavy, and may be provided with an eye 31 by means of which it can be lifted from its seat. If desired, the upper edge of the inner receptacle may be reinforced by means of a strap 32, while an angle bar 33 may be secured near the top of the outer receptacle for a purpose hereinafter set forth.

When a proper mixture of air and gas is burned at the openings in the tops of the burner tubes 5, a circulation of the liquid will occur through the rising of the hotter portions thereof. The liquid will flow in and out through the openings 26 so that the temperature of the liquid within the inner receptacle will be kept nearly as high as in the outer receptacle. If the heat applied is sufficient to cause the liquid to boil up, the angle bar 33 will prevent the liquid from flowing out over the edge of the outer receptacle.

When holes are formed in the bottom of the inner receptacle, the hottest liquid en-

ters through these holes and the sediment in this inner receptacle is kept in constant agitation, and this sediment settles on the articles being treated within the inner receptacle. This also occurs when holes are formed in the sides of the inner receptacle at any considerable distance from the surface of the liquid. This agitation is avoided by providing the inner receptacle with the holes 26 near the upper edges of its sides. Any sediment from the articles being treated in this double tank will fall to the bottom of the inner receptacle, where it will remain practically undisturbed, because of the liquid at the top of the inner receptacle being hotter than at the bottom. At proper intervals of time, the valve 30 is removed and the inner receptacle is slowly lifted out, the liquid contents thereof flowing down through the short pipe 29 into the outer receptacle. When the inner receptacle is entirely free, the pipe 29 may be removed and the sediment permitted to drain out, a hose being employed to wash out this receptacle if desired. After being cleaned, the inner receptacle is replaced, the liquid in the outer receptacle flowing up through the pipe 29, after which the valve 30 is replaced. Very little of the liquid is wasted when the tank is cleaned and none of the sediment is kept in suspension as it is when heat is applied directly to the inner receptacle or when the bottom of the inner receptacle is perforated. If desired, the sides and ends of the inner receptacle may be so low as to be below the level of the liquid as shown in Fig. 4, in which case the holes 26 are unnecessary. When the holes 26 are used, the articles being treated should be below the level of these holes.

I claim:

1. In a double tank, the combination of an outer receptacle and a second receptacle within the first and spaced therefrom, said inner receptacle having an imperforate bottom and having sides formed with a row of openings near their upper edges, the sides below the openings being imperforate.

2. In a double tank, the combination of an outer receptacle, a second receptacle within the first and spaced therefrom, and a discharging device mounted on the bottom of the inner receptacle and adapted to permit the liquid contents thereof to be decanted.

3. In a double tank, the combination of an outer receptacle, supports within the same, a second receptacle within the first resting on the supports, the bottom of the second receptacle being imperforate and the sides being formed with holes along the up-

per edges, the sides below the openings being imperforate, a heating device below the outer receptacle, and a casing surrounding the tank.

4. In a double tank, the combination of an outer receptacle, a second receptacle within the first and spaced therefrom, a piece of pipe connecting to the bottom of the inner receptacle, and a valve for closing the upper end of said pipe.

5. In a double tank, the combination of an outer receptacle, a second receptacle within the first and spaced therefrom and having an opening in its bottom, a ring secured to the bottom around the opening, a short piece of pipe screwed into the ring, and a valve closing the upper end of said pipe.

6. In a double tank, the combination of an outer receptacle, a second receptacle within the first and spaced therefrom and having an opening in its bottom, a ring secured to the bottom around the opening, a short piece of pipe screwed into the ring, a valve closing the upper end of said pipe, and means to heat the contents of the outer receptacle.

7. In a double tank, the combination of an outer receptacle, a second receptacle within the first and spaced therefrom and having an opening in its bottom, a ring secured to the bottom around the opening, a short piece of pipe screwed into the ring, a valve closing the upper end of said pipe, a casing extending around the outer receptacle, and a pair of burner tubes extending below the outer receptacle.

8. In a double tank, the combination of an outer receptacle, a second receptacle within the first and spaced therefrom and having an opening in its bottom, a ring secured to the bottom around the opening, a short piece of pipe screwed into the ring, a valve closing the upper end of said pipe, and means to heat the contents of the outer receptacle, said inner receptacle having a line of holes through its walls above the middle thereof.

9. In a double tank, the combination of an outer receptacle, a second receptacle within the first and spaced therefrom, the top of the sides of the inner receptacle being below the top of the sides of the outer receptacle, an inwardly extending flange on the walls of the outer receptacle above the top of the sides of the inner receptacle, and means to apply heat to the bottom of the outer receptacle.

In testimony whereof I sign this specification.

WYMAN C. PARKER.
